UNITED STATES PATENT OFFICE.

HOWARD M. DUDLEY, OF PHILADELPHIA, PENNSYLVANIA, ASSIGNOR, BY MESNE ASSIGNMENTS, TO THE FIFTH AVENUE BANK OF NEW YORK, OF NEW YORK, N. Y., A CORPORATION OF NEW YORK.

APPARATUS FOR DYEING, SCOURING, OR OTHERWISE TREATING YARN AND OTHER FIBERS IN THE HANK OR SKEIN.

Application filed August 5, 1921, Serial No. 489,935. Renewed June 22, 1923.

To all whom it may concern:

Be it known that I, HOWARD M. DUDLEY, a citizen of the United States, and a resident of Philadelphia, Pennsylvania, have invented certain new and useful Improvements in Apparatus for Dyeing, Scouring, or Otherwise Treating Yarn and Other Fibers in the Hank or Skein, of which the following is a specification.

10 My invention relates more particularly to that type of machine in which the hanks or skeins of yarn or fiber to be dyed or otherwise treated, are suspended from sticks and dip into a closed tank or chamber containing 15 the dyeing or treating liquid, and in which provision is made for the movement of such liquid; preferably in a plurality of directions, in order that all portions of such skeins or hanks of yarn or other fibers shall be subjected 20 equally to the action of the dyeing or treating liquid.

The principal object of my present invention is to provide means disposed externally of the dyeing or treating chamber for 25 effecting movement of the liquid therein; which means may include a liquid containing casing in liquid tight engagement with the dyeing or treating chamber and containing passages in communication with the top and 30 bottom of the same; with a propeller disposed in said casing for effecting movement of the liquid for passage in opposite directions in said dyeing or treating chamber as may be desired.

35 A further object of my invention is to provide baffle plates in the upper and lower portions of the dyeing or treating chamber in order that the moving liquid may be prevented from forming currents that would 40 tend to avoid portions of the yarn or fiber under treatment; such baffles breaking up the moving liquid and insuring engagement therewith of all portions of the hanks or skeins of yarn or fiber under treatment.

45 In my present construction, I employ a vertically movable frame or support for the 50 yarn or fiber-carrying sticks, as in my companion application, such frame or support being so mounted that when the dyeing or treating liquid is being moved in one direction, it will have a tendency to lift said sticks, and the yarn with the same, and in such action will cause a separation between

the sticks and the yarn supported thereby at the point of contact, whereby such contacting portion, which is more or less difficult of access by the liquid, shall receive as great an amount of contact with the liquid as the balance of the skein or hank. 55

In my improved apparatus, which may be employed for dyeing, scouring, or otherwise treating yarn or fiber in the skein or hank, the means for effecting movement of the liquid within the dyeing or treating chamber are located wholly outside said chamber, so that while the liquid may be moved in two directions within the chamber, the circulation is from an outer casing into the chamber, and from the chamber to such outer casing. In other words, the casing receiving 60 the propeller or liquid moving member is disposed outside the dyeing or treating chamber, and provided with passages leading to the upper and lower portions of the latter; the liquid for instance, when discharged into the upper portion of the chamber, leaving the latter from the lower portion thereof and passing to the external casing, and when introduced into the lower portion of the chamber, leaving the latter from 65 the upper portion thereof and passing into the external casing. 70

These and other features of my invention are more fully disclosed hereinafter; reference being had to the accompanying drawing, in which:

Figure 1, is a longitudinal sectional view of dyeing or fiber-treating apparatus within the scope of my invention.

Fig. 2, is a cross sectional view on the line 90 II—II, Fig. 1.

Fig. 3, is a cross sectional view on the line III—III, Fig. 1, and

Figs. 4 and 5 are detached views illustrating details of my invention. 95

My improved apparatus is of the closed chamber type, whereby the dyeing or treating liquid within the same may be moved in a plurality of directions; that is to say, downwardly through the hanks or skeins of 100 yarn or fiber, and then upwardly through the same; changes in direction of movement of the liquid being effected readily and without altering the character of the power-applying means, which are disposed externally 105 of the dyeing or treating chamber.

In the drawing, 1 represents the dyeing or treating chamber, which may comprise a suitable base 2, and side and end walls 3 and 4, with removable top or cover 5, in liquid-tight, or substantially liquid-tight engagement with the side and end walls of the chamber, so that under the motion imparted thereto, the liquid within the chamber will have no tendency to leak or seep out beneath the top or cover 5. Within the chamber so provided, the hanks or skeins of yarn or fiber, indicated at X, are disposed for treatment.

The hank or skein supporting means disposed within the dyeing or treating chamber are suspended by bolts 10 connected to the cover 5, and are substantially like those disclosed in my companion application filed of even date herewith. Such supporting means may comprise end cross-bars 11, to which said bolts 10 are secured; said cross-bars carrying at their opposite ends boxes 12, for the reception of the ends of rails 13, extending the length of the dyeing or treating chamber, said rails being apertured at 14, for the reception of yarn- or fiber-carrying sticks 15, which are held thereto by the retaining plates 16, constructed and operated in the manner set forth in my companion application, and confined against lateral movement. Provision is made for slight vertical movement of said sticks; the boxes 12, in which the ends of the rails 13, carrying said sticks, are disposed, providing space for vertical movement of the rails, and said sticks follow with them. In addition, the cross-bars 11, support a foraminous frame disposed directly over the hanks or skeins of yarn or fiber, through which the moving liquid passes; such frame being made up of side rails 20, and cross-bars 21, spaced a suitable distance apart. As this arrangement is more or less common in apparatus of this character, it would seem to require no specific description as to exact character or function.

Supports 22, depend from the boxes 12, and adjustably carried by the lower ends of these supports, are rails 23, secured to the supports by pins 24, and having cross sticks 25, which pass through the lower portion of the hanks or skeins of yarn or fiber and restrain the same from excessive upward movement when the liquid in the chamber is caused to move in an upward direction, and lift the hanks or skeins of yarn or fiber from the upper sticks. Below the hanks or skeins of yarn or fiber, I provide a foraminous frame comprising side rails 20^a, and cross-bars 21^a, of the same general character as the frame disposed above the hanks or skeins of yarn or fiber, and designed to perform the same function as said upper frame.

Disposed externally of the chamber, I provide means for moving the liquid through the dyeing or treating chamber in opposite

directions, such means including a casing 30, of special character, having a mid section 31, substantially circular in cross-section, which mid section broadens outwardly and flattens toward the upper and lower portion of the dyeing or treating chamber to form the passages 32 and 33, the discharge outlets 32^a and 33^a, thereof, being substantially rectangular and elongated and registering with ports or openings 34 and 35, formed in the end wall 4 of the dyeing or treating chamber. The combined inlet and outlet ports or openings 34 and 35 are disposed above and below the hanks or skeins of yarn or fiber, and such ports or openings have an area substantially equal to the cross sectional area of the circular mid portion of said casing, intermediate the passages 32 and 33.

Suitably disposed in the casing 30, preferably at the circular mid section of the same, is a propeller wheel 40, carried by a shaft 41, which may be journaled in suitable bearings 42 and 43, carried by the casing, and motion to turn said shaft may be imparted by a belt 44, passing over a pulley 45, carried by the end of said shaft 41, and driven by a motor 46. When driven in one direction, that indicated by the arrow *a*, for instance, the liquid will be driven in the direction indicated by the arrow *x*; being drawn out of the lower portion of the dyeing or treating chamber through the port 35, into the passage 33, and discharged by said propeller through the passage 32, and port 34, into the upper part of said dyeing or treating chamber. When the wheel is driven in the direction of the arrow *b*, the liquid will be driven out of the top of the dyeing or treating chamber through the port 34, into the passage 32, into the dyeing or treating chamber in the direction of the arrows *y*, indicated by dotted lines.

In order that the liquid may be prevented from setting up currents or eddies which would tend to pass through one portion of the hanks or skeins and omit other portions of the same, the interior of the dyeing or treating chamber may be provided with a series of baffle plates 47 and 48; those indicated at 47 being carried by the top or cover 5 of the dyeing or treating chamber, while those indicated at 48 being carried at the bottom of the chamber. It will be understood, of course, that a greater or less number of baffle plates, capable of performing the desired function, may be employed, as desired.

In practice, as I have described in my companion application, the hanks or skeins of yarn or fiber will be lifted from the upper sticks when the dyeing or treating liquid moves in one direction, permitting complete contact of the liquid with all parts of said hanks or skeins of yarn or fiber, and such action is illustrated in Figs. 4 and 5.

While I described a propeller mounted upon a horizontal shaft and disposed in the circular mid section of the external casing for moving the liquid in the dyeing chamber, it will be understood that such propeller may be mounted upon a vertical shaft; the casing being modified accordingly, and such shaft being driven so as to move the liquid from said casing through the dyeing or treating chamber in two directions. In all instances, however, such movement of the liquid takes place in a casing disposed externally of the dyeing or treating chamber.

15 While I have shown in the drawings ports or openings 34 and 35, formed in the end wall 4, of the dyeing or treating chamber and which register with the combined inlet and discharge openings 32^a and 33^a of the 20 external casing respectively, as rectangular in shape and not extending the entire width of the dyeing or treating chamber, it will be understood that their shape may be changed or altered as may be desired, that in some 25 instances it may be oval, and that in other instances where rectangular openings are provided, it may extend the full width of the chamber without departing from my invention. The appended claims are intended 30 to cover a structure having an opening for the purpose described, capable of performing the desired function.

I claim:

1. The combination, in fiber-treating apparatus, of a vat or tank providing a chamber, a movable frame disposed in said chamber for supporting hanks or skeins of yarn to be dyed or treated, a casing secured to the end of said tank; the latter having rectangular openings extending width-wise of the tank at top and bottom in communication with said casing, and a propeller in said casing for moving the liquid through the tank chamber in opposite directions; said casing having a circular mid section providing a propeller space and passages leading therefrom which gradually flatten to provide openings registering with the rectangular openings in the tank.
2. In a dyeing machine, in combination, a dyeing or treating chamber, a supporting frame disposed in said chamber for supporting the material under treatment, means disposed externally of said chamber for moving the liquid therein in opposite directions and having conduits leading to spaced parts of said chamber at opposite sides of said frame, said conduits having elongated ports for distribution of liquid in the chamber, one of said conduits conducting liquid to the chamber during flow in one direction and receiving liquid from the chamber during flow in the opposite direction.
3. In a dyeing machine, in combination, 65 a dyeing or treating chamber, a supporting

frame disposed in said chamber for supporting the material under treatment, means disposed externally of said chamber for moving the liquid therein in opposite directions and having conduits leading to spaced parts of said chamber at opposite sides of said frame, said conduits having elongated ports for distribution of liquid in the chamber, one of said conduits conducting liquid to the chamber during flow in one direction and receiving liquid from the chamber during flow in the opposite direction, and means for mounting said supporting frame for bodily movement in opposite directions under the influence of the moving liquid.

4. In a dyeing machine, in combination, a dyeing or treating chamber, a supporting frame disposed in said chamber for supporting the material under treatment, means disposed externally of said chamber for moving the liquid therein in opposite directions and having conduits leading to the upper and lower parts of said chamber, said conduits having elongated ports for distribution of liquid in the chamber above and below said frame, said liquid entering the chamber through the upper conduit and discharging through the lower conduit when moving in one direction, and entering at the lower conduit and discharging at the upper conduit when moving in the opposite direction.

5. In a dyeing machine, in combination, a closed dyeing or treating chamber, a supporting frame disposed in said chamber for supporting the material under treatment, means disposed externally of said chamber for moving the liquid therein in opposite directions and having conduits leading to the upper and lower parts of said chamber, said conduits having elongated ports for distribution of liquid in the chamber above and below said frame, said liquid entering the chamber through the upper conduit and discharging through the lower conduit when moving in one direction, and entering at the lower conduit and discharging at the upper conduit when moving in the opposite direction, and means for mounting said supporting frame for bodily vertical movement in opposite directions under the influence of the liquid currents in said chamber.

6. In a dyeing machine, in combination, a dyeing or treating chamber, a supporting frame disposed in said chamber for supporting the material under treatment, means disposed externally of said chamber for moving the liquid therein in opposite directions, and having conduits leading to spaced parts of said chamber at opposite sides of said frame, said conduits having elongated ports for distribution of liquid in the chamber, said conduits being formed to provide an intermediate propeller section communicating with the conduits and being gradual-

ly flattened and merging with said conduits.

7. In a dyeing machine, in combination, a dyeing or treating chamber, a supporting frame disposed in said chamber for supporting the material under treatment, means disposed externally of said chamber for moving the liquid therein in opposite directions, and having conduits leading to spaced parts of said chamber at opposite sides of said frame, said conduits having elongated ports for distribution of liquid in the chamber, said conduits being formed to provide an intermediate propeller section communicating with the conduits and being gradually flattened and merging with said conduits, one of said conduits conducting liquid to the chamber and the other conduit receiving liquid therefrom during flow in one direction, and said one conduit receiving liquid from the chamber, and the other conducting liquid thereto during flow in the opposite direction.

8. In a dyeing machine, in combination, a closed dyeing or treating chamber, a supporting frame disposed in said chamber for supporting the material under treatment, means disposed externally of said chamber for moving the liquid therein in opposite directions, and having conduits leading to upper and lower parts of said chamber, said conduits being flattened adjacent the ends communicating with said chamber and having elongated ports for the distribution of liquid in the chamber, a pro-

35 peller housing connected with said conduits, and a reversible propeller mounted therein, the liquid entering the chamber through the upper conduit and discharging at the lower conduit when moving in one direction, and entering at the lower conduit and discharging at the upper conduit when moving in the opposite direction.

40 9. In a dyeing machine, in combination, a dyeing or treating chamber, a supporting frame disposed in said chamber for supporting the material under treatment, means disposed externally of said chamber for moving the liquid therein in opposite directions, and having conduits leading to upper and lower parts of said chamber, said conduits being flattened adjacent the ends communicating with said chamber and having elongated ports for the distribution of liquid in the chamber, a propeller housing connected with said conduits, and a reversible propeller mounted therein, the liquid entering the chamber through the upper conduit and discharging at the lower conduit when moving in one direction and entering at the lower conduit and discharging at the upper 45 conduit when moving in the opposite direction, and means for mounting said supporting frame for bodily vertical movement in opposite directions under the influence of liquid currents in said chamber.

50 55 In witness whereof I have signed this specification.

HOWARD M. DUDLEY.
